HARRY BRIDGMAN SMITH, OF BROOKLYN, NEW YORK.

PAPER BOX CONSTRUCTION.

Application filed June 1, 1918, Serial No. 237,709.

Renewed February 24, 1920. Serial No. 360,765.

To all whom it may concern:

Be it known that I, HARRY BRIDGMAN SMITH, a citizen of the United States, residing at Brooklyn, in the county of Kings and State of New York, have invented new and useful Improvements in Paper Box Constructions, of which the following is a specification.

This invention relates to improvements in paper box construction, and pertains more particularly to covered paper box shells.

The present invention has for its object the production of a covered box shell or box member by an assembly of box blank and covering sheet or blank in such form as to simplify and expedite the manufacture of the covered shell or member and enable the manufacturing cost to be greatly decreased, and the daily output greatly increased.

This result is obtainable by reason of the fact that I have discovered an entirely new continuous method of providing an assembly of box and covering blank which greatly simplifies the method of producing the covering blank used in providing the shell formation.

A distinguishing characteristic of the covered box of my present invention lies in the fact that free portions of the covering blank carried by an upstanding wall of the shell are adhesively attached to the exterior faces of adjacent walls of the shell, thus locating such portions as an external covering element for the wings of the latter walls, these portions thus overlying the corner produced by the meeting wings. Another distinguishing feature of the present invention is the production of an embryo box assembly of the covering and box blanks, this assembly being provided in the flat; this permits of the production of successive assemblies in a more or less continuous operation and in a form adapted for the succeeding operations in completing the shell formation. Another characteristic lies in the fact that these externally-applied portions of the covering blank are of a two-ply formation at the marginal edge portions of the open shell. So far as I am aware, I am the first to produce a shell construction or apply a covering blank in this way.

To these and other ends, the nature of which will be readily understood as the invention is hereinafter disclosed, said invention consists in the improved construction

and arrangement of parts hereinafter more fully described, illustrated in the accompanying drawings, and more particularly pointed out in the appended claims.

In the accompanying drawings, in which similar reference characters indicate similar parts in each of the views:—

Fig. 1 is a perspective view illustrating the initial stages of one way of assembling a box blank with its covering blank in accordance with the method which I have discovered.

Figs. 2 to 4 are perspective views showing stages of the shell manufacture.

Fig. 5 is a perspective view of a completed shell.

A box having the characteristics of the present invention is illustrated in Fig. 5, but for the purpose of more clearly indicating these characteristics, I will first describe a preferred way in which the shell of Fig. 5 may be produced, it being understood, however, that the shell may be formed in other ways, claims for a particular method as such being reserved for a companion application.

In the preferred method, the covering blank is initially in the form of a web or sheet 10 having a width in excess of one of the dimensions of the flat box blank. In the drawings I have shown this dimension as that corresponding to the length of the shell, but this may obviously be reversed. Web or sheet 10 has one of its faces coated with adhesive, and on this face are placed successive box blanks 11 while the latter as well as the web are flat, these blanks being shown as of the usual simple form of box blank having a body portion a , side wings a' and end wings a'' . These box blanks are arranged spaced apart from each other at approximately equal distances, with the longitudinal edges of the blank extending at substantially right angles to the direction of length of the web, thus practically "spotting" the flat box blanks on the adhesively-coated face of the web, as shown at A in Fig. 1.

As will be seen, this "spotting" serves to space the end wings of the box blank from the edges of the web and from each other, and the succeeding stage of the assembly is that of turning over these margins of the web over the edges of and on to the top faces of the positioned blank or blanks, thus caus-

ing the margins to extend over and be adhesively secured to the exposed faces of the end wings of the box blank or blanks. Since this infolding of the web margins is continuous throughout the length of the web, the portions of the web margins which do not overlie the box blank end wings extend in overlying relation and are adhesively secured to the portion of the web adjacent to these margins which are not covered by the "spotted" box blank, thus giving a two-ply structure at these marginal portions, this general operation being shown at B in Fig. 1.

15. There is thus provided a web having "spotted" box blanks at regularly spaced intervals in the direction of length of the web with marginal portions turned over on to the end wings of the box blank.

20. The succeeding operation is that of slitting the web to provide for the formation of certain free flaps or laps in the covering blank, the slits for this purpose extending longitudinally of the web substantially on lines corresponding to the ends of the side wings of the positioned blanks, as for instance indicated at 12 in Fig. 1, these slits extending from an end of the end wing of one positioned blank to the opposite end of 30 the end wing of the adjacent positioned blank, the slits extending parallel to the edges of the web, producing a structure such as shown at C in Fig. 1.

35. The web is then divided transversely into intermediate adjacent box blanks, as for instance on the line 13 of Fig. 1, the separated assembly corresponding to Fig. 2 of the drawings with the exception that the marginal portions 14 of the covering blank thus produced are still in the flat, these portions 40 14 being provided by the web material between adjacent "spotted" box blanks. And it may be noted that in "spotting" the box blanks, the distance between adjacent blanks is made sufficient to provide for these marginal portions 14 for each blank.

50. These marginal portions 14 are then turned in, the result being that each of the wings of the box blank—which form the up-standing walls of the box—have their marginal edges covered—thus completing the finish of these marginal portions—while the blanks are still in the flat. At the same time there are produced free flaps 15 of the covering blank—also in the flat—these flaps being the result of the presence of slits 12. This construction provides an embryo box assembly of the blanks—an assembly provided in the flat—which may be produced 60 as a product complete in itself ready to be fed or transported to apparatus for the formation of the finished box. As far as I am aware, I am the first to provide an embryo box assembly of the character stated where- 65 in the cover blank has been completely ap-

plied to the box blank with the marginal portions inturned and affixed while the assembly is substantially flat.

Depending upon the character of the box to be produced, the marginal portions 16 of the end wings will be provided with an adhesive coating on the upper surface. If the shell is to be utilized in the formation of a "neck" box, this adhesive coating will extend throughout the length of this marginal portion 16, and the upper surfaces of marginal portions 14 will also be similarly coated. Where, however, the shell is to be utilized otherwise, this adhesive application is practically limited to those portions of margins 16 which overlie flaps 15. This application of the adhesive coating to these margins may be provided while the covering blank is in web form or after the latter has reached the embryo assembly stage.

75. After the embryo assembly has been made as in Fig. 2, the side wings—the wings which do not carry flaps 15—are folded into up-standing position, as in Fig. 3, after which the end wings—carrying flaps 15—are folded to the upstanding position, producing the structure of Fig. 4. Flaps 15 are then folded into contact with the outer or exterior faces of the upstanding side wings, 80 thus completing the box formation with flaps 15 adhesively secured to the external face of the side wings, as in Fig. 5.

90. As will be readily understood, the depth of margins 16 is dependent on the depth of the fold made at the margins of the web, and this may obviously be to an extent sufficient to overlie the entire surface of the end wings. It will be understood, of course, that for the purpose of uniformity, margins 14 should extend to a corresponding point with respect to the side wings, and this latter will be controlled by the spacing of the "spotted" box blanks.

95. In the drawings I have shown flaps 15 110 as carried by the end wings, but it will be obvious that they may be carried by the side wings, in which case they would be applied to the outer faces of the end wings, this change resulting by simply "spotting" the 115 box blanks with the direction of length extending longitudinally instead of transversely of the web. In either case, however, there is presented a structure in which a wing of the assembly carries a covering 120 blank flap or lap which is applied to the external covered face of an adjacent wing when both wings are in upstanding position, the flap forming the outer ply of the wing to which it is attached.

125. As will be seen, each flap 15 has at least that marginal portion which is located at the open top of the completed shell of a two-ply formation, the extent of the double ply structure depending upon the depth of mar- 130

gin 16. As a result, the connections between adjacent wings at the marginal edges of the open top of the shell are reinforced; by increasing the depth of inturning of margin 5 16, the depth of this two-ply construction will be correspondingly increased.

It is to be understood that I prefer to locate the flaps 15 at an end—or side—of the shell on the same wing, thus providing for 10 simplicity of production and of assembly, but it will be understood that the invention is not limited in this respect, since I may obviously arrange the flaps in other locations.

15 As heretofore pointed out, the invention is not limited to the stage production herein disclosed, although this is preferred because the various operations required to produce the described assembly may be carried 20 on continuously and at great speed as compared with other methods known to me.

This general construction is adapted for use in connection with an ordinary shell or box member, or it may be utilized in connection 25 with the production of a "neck" box, by the insertion therein of the usual neck strip which, when employed, will be held in place by the marginal portions 14 and 16 being adhesively coated as heretofore indicated. 30 And while I have shown flaps 15 as of a length less than that required to completely cover the external face of the wing to which they are adhesively attached, it will be understood that these lengths of 35 flaps may be increased even to a point where they completely cover the wing face, and this can be provided in practicing the method disclosed in Figs. 1 to 4 by increasing the distance between "spotted" blanks 40 to a point where the distance between the opposing ends of the end wings of adjacent blanks will equal the length of the wing to be covered. In such case, the excess material between adjacent blanks over that required 45 to produce the desired margin 14 may be readily removed at the time when the web is being severed.

While I have herein shown and described several forms of the present invention and 50 various ways in which it can be produced, it will be readily understood that changes and modifications therein may be found desirable or necessary in meeting the exigencies of use, and I desire to be understood as res- 55 serving the right to make any and all such changes or modifications as may be found desirable or essential, in so far as the same may fall within the spirit and scope of the invention as expressed in the accompanying 60 claims when broadly construed.

What I claim is:—

1. A covered box shell comprising a box blank and a covering blank assembled to produce a shell with upstanding walls, said cov- 65 ering blank, including a flap extending in-

tegrally from one wall and adhesively secured to the exterior face of an adjacent wall, said flaps including a two-ply structure forming a reinforce at the juncture of the walls. 70

2. A covered box shell comprising a box blank and a covering blank assembled to produce a shell with upstanding walls, said covering blank including flaps each overlying the points of juncture of said walls and 75 adhesively secured to external faces of box walls, each flap including a two-ply formation acting as a reinforce at the junction point which it overlies.

3. A covered box shell comprising a box blank and a covering blank assembled to produce a permanently "set up" shell with upstanding walls, said covering blank including a wing and flap of substantially equal width and of greater width than the 85 wall to which the wing is applied to permit the wing to overlie the marginal edge of and extend on to the inner face of such wall, said flap being folded into multi-ply formation on a line approximating the marginal 90 edge of the wing and being applied to the exterior face of an adjacent wall, the folded flap forming a two-ply formation adjacent the marginal edge of the wall to which it is secured. 95

4. An embryo assembly for covered box shells comprising a box blank and a covering blank adhesively secured in superposed relation with the box blank in the flat, said box blank including wings, said covering 100 blank having portions folded to overlie marginal edges of and be adhesively secured to opposite faces of the wings, said covering blank also having free flaps of multiply formation extending from opposite ends of predetermined wings of the box blank and adapted for adhesive connection to the exterior faces of adjacent wings when the assembly is folded to box formation. 105

5. A paper box blank adapted for production by a continuous method as described, and comprising a shell blank having rectangular side and end wings of equal width and a cover blank to which the shell blank is adhesively secured in facial contact 110 throughout the entire extent of the shell blank, the cover blank having wings overlying two opposite shell wings and other wings secured to the other two opposite shell wings and having flaps of substantially the 115 same width as the shell wings and extending beyond the ends of said shell wings and severed from adjacent ends of the cover wings secured to the first named opposite shell wings, the blank being arranged for 120 folding into box form with said flaps adhesively secured on the outer surfaces of the cover blank overlying the shell wings first mentioned to act as corner stays. 125

6. A paper box structure comprising a 130

shell blank having side and end wings turned up at a right angle to the central body portion, and a cover blank adhesively secured to the shell blank in facial contact throughout the entire extent of the shell blank, said cover blank having side wings overlying two opposite shell wings, and also having other wings overlying the other two opposite shell wings, said last-named cover 10 wings having end flaps extending beyond the

ends of the underlying shell wings and of substantially the same width as said shell wings, said flaps being turned about the box corners and adhesively secured to outer surfaces of the cover material overlying the 15 first named shell wings.

In testimony whereof I have hereunto set my hand.

HARRY BRIDGMAN SMITH.
